CATALYTIC ISOMERIZATION OF
SATURATED HYDROCARBONS

Martin de Simó, Piedmont, and Frank Matthew McMillan and Harry Ashley Cheney, Berkeley, Calif., assignors to Shell Development Company, San Francisco, Calif., a corporation of Delaware

No Drawing. Application October 31, 1940,
Serial No. 363,670

6 Claims. (Cl. 260—676)

The present invention relates to a process for the catalytic isomerization of hydrocarbons. More particularly, the invention relates to the catalytic isomerization of saturated hydrocarbons having from four to nine carbon atoms. Particular aspects of the invention are the catalytic conversion of normal butane and normal pentane to isobutane and isopentane, respectively, and the conversion of methylcyclopentane and dimethylcyclopentane to cyclohexane and methylcyclohexane, respectively.

The normal paraffin hydrocarbons may be obtained in a relatively pure state in large quantities from petroleum and natural gas. These hydrocarbons are chemically quite unreactive and have poor ignition characteristics. Their corresponding branched chain isomers, on the other hand, are chemically much more reactive and have excellent ignition characteristics but occur naturally only to very limited extents. The branched chain isomers may be readily alkylated with olefines, for example, to produce saturated hydrocarbons which are especially desired for premium and aviation gasoline, and they may be readily dehydrogenated to the respective tertiary olefines which, in turn, are excellent starting materials for the synthesis of a wide variety of useful and valuable products. In view of the abundance of these normal hydrocarbons and the ever increasing demand for their branched chain isomers, a commercially practical process for the conversion of the normal isomers to their branched chain isomers is in demand.

An object of the invention is to provide an improved, practical and economical process for the catalytic isomerization of saturated hydrocarbons to their more highly branched isomers. A particular object is to provide a more advantageous process whereby normal butane and normal pentane may be converted with improved yields and more practical catalyst life to isobutane and isopentane, respectively. Another particular object is to provide an improved method for the isomerization of saturated cycloparaffins such as cyclohexane, methylcyclohexane, methylcyclopentane and dimethylcyclopentane.

Another particular object of the invention is to provide a process whereby lower boiling saturated distillates of the nature of gasoline may be isomerized efficiently and more advantageously to increase their ignition properties. Other objects of the invention will be apparent from the following description of the process.

In its more general aspect the process of the invention comprises isomerizing the hydrocar-

bons or mixture of hydrocarbons by treating them in the presence of a hydrogen halide promoter with catalysts of a specified composition prepared in a specified manner.

While the process is generally applicable to the isomerization of saturated hydrocarbons, it is especially advantageous for the isomerization of normal butane, normal pentane, methylcyclopentane and dimethylcyclopentane. These hydrocarbons may be obtained in large quantities as individual compounds in a relatively pure state. The hydrocarbon treated need not necessarily be a pure individual hydrocarbon, however, but may be a mixture of one or more hydrocarbons. Thus, the invention provides a practical process for converting the normal butane and normal pentane contents of commercial hydrocarbon mixtures, such as are obtained from natural gas, petroleum distillates, cracked distillates, etc. to the more valuable branched chain isomers. Especially suitable mixtures of hydrocarbons are the so-called butane-butylene fractions and pentane-ethylene fractions from which unsaturated hydrocarbons have been substantially removed. Treatment of such mixtures, such as obtained for instance as a by-product in the sulfuric acid alkylation of isoparaffins, results in very materially increasing their content of branched chain isomers and converting them to suitable raw materials for reuse in the alkylation process. Technical butane and pentane fractions, such as those containing from 70% to 90% of the normal isomer and from 2% to 30% of the branched chain isomer, may be conveniently treated in accordance with the process of the invention and their content of branched chain isomers materially increased without loss due to decomposition and side reactions, and while realizing a maximum active life of the catalyst employed. Other mixtures of saturated hydrocarbons, such as those of straight run gasoline, casing head gasoline, etc. containing appreciable quantities of normal butane, normal pentane, cyclohexane, methylcyclohexane or other lower boiling non-branched saturated hydrocarbons, may be advantageously treated to produce products which are suitable for alkylation with olefines and have superior ignition characteristics.

The hydrocarbon or mixture of hydrocarbons treated is preferably substantially free of materials which are polymerized by aluminum chloride under the reaction conditions. According to the preferred embodiment of the invention, any olefines, diolefines or other detrimental impurities in the hydrocarbon or hydrocarbon mixture

to be treated are removed prior to the isomerization by a suitable treatment, such as with a mineral acid, hydrogenation or with a portion of spent catalyst from the process.

The various hydrocarbons to be isomerized are treated according to the process of the invention with solid promoted aluminum chloride catalysts prepared in a specific manner. Thus, the catalysts employed in the present process are prepared by mixing certain inorganic promoters with sufficient aluminum chloride to form a solid cake and heating the mixture while under superatmospheric pressure to a temperature sufficiently high to fuse the aluminum chloride, cooling the mass to produce a solid cake, and then crushing said cake into small irregular fragments. The catalysts produced by this procedure are quite different than the impregnated catalysts prepared by older methods and possess valuable and unexpected properties and characteristics.

One of the advantages of the present process is due to the greater activity and selectivity of the catalyst employed. This increased catalytic activity is very pronounced in some cases and less so in others, and depends primarily upon the method of preparation and the particular material with which the aluminum chloride is combined. The more active catalysts employed in the present invention are true catalyst combinations. Their increased catalytic activity is due to a promoting effect of the so-called carrier which is materially enhanced by the described method of preparation. Another important advantageous characteristic of the catalysts which is utilized in the present process is their superior mechanical strength. Due to their superior properties in this respect they can be employed in place of lump aluminum chloride in larger, more economically employed beds. They also suffer much less disintegration during use, and consequently can be used for much longer periods of time before the efficiency of the bed becomes impaired by channeling, etc. due to disintegration.

Preferred materials to be combined with aluminum chloride in the preparation of the catalysts for the present process are the various siliceous and/or aluminous materials of natural or synthetic origin which may contain an appreciable amount of firmly bound or strongly adsorbed water. Suitable materials of this category are, for example, the naturally-occurring minerals and clays such as pipe clay, bauxite, fuller's earth, bentonite, kaolin, Florida earth, meerschaum, infusorial earth, kieselguhr, diatomaceous earth, montmorillonite, the permutites and the like; the various treated clays and clay-like materials; the artificially prepared materials such as activated alumina, the artificial permutites and the like. These materials are preferably but not necessarily partially dehydrated by heating in a dry atmosphere at a temperature somewhat higher than that at which they are to be employed.

Of these materials and similar materials of this category, "Activated Alumina" and "Porocel" are found to be particularly effective. "Activated Alumina" is a trade-mark name for a highly adsorptive alumina prepared and sold by the Aluminum Ore Company. It is designated "Activated Alumina" because of its active adsorptive properties and should not be confused with various aluminas which have been made catalytically active and are thus said to have been activated. "Activated Alumina" is said to be prepared according to the method more fully described and claimed in United States Patent 1,868,869. Other

methods for the preparation of suitable activated aluminas are described in United States Patent 2,184,235 and German Patent 405,238. "Porocel" is a trade name for an especially adsorptive alumina prepared by the Porocel Corporation from a selected bauxite. Although highly active (adsorptive) materials such as "Activated Alumina" and "Porocel" are much preferred, it is to be particularly noted that it is the particular surface composition and characteristics of these materials and not their adsorptive quality which are responsible for their superiority in the catalyst used in the process of the present invention. These materials, as purchased, are usually activated (calcined) just sufficiently to produce their maximum adsorptive ability and further calcination results in a decrease in their adsorptive properties. It is found, however, that these materials may exhibit an even greater promoting effect upon the aluminum chloride if they are calcined somewhat further than to give the maximum adsorptive ability. Care should be exercised, however, not to over-calcine or "dead-burn" the materials since if over-calcined they lose their promoting effect and instead of producing a superior promoted catalyst with aluminum chloride, they merely act as diluents.

Although materials of the above classes are active in promoting the isomerizing ability of aluminum chloride and produce the most active catalysts, any of the common catalyst carriers or supporting materials, such as activated charcoal, crushed coke, crushed brick, pumice, porcelain chips, chamotte, asbestos and the like, may also be used, if desired. The most important advantages offered by these latter materials are their high mechanical strength and low cost. They are most advantageously used in conjunction with one or more of the above-mentioned promoting materials.

The promoting and carrier material may be in the form of small broken pieces or as a fine powder, and may be employed either singly or in admixture with one another. Thus, for example, an excellent catalyst of high mechanical strength and low cost may consist of anhydrous aluminum chloride, powdered "Porocel," and 8-10 mesh pumice.

For the preparation of the catalyst any substantially anhydrous aluminum chloride such as the powdered commercial product may be used. The catalyst is preferably prepared, however, from materials which are as low as practical in iron. In such cases where one or more of the materials contain appreciable quantities of iron, the deleterious effect of this substance may be counteracted to a considerable extent by the addition of a small quantity of aluminum into the mixture prior to fusing to form the cake. Instead of adding aluminum powder, filings, turnings or the like, the same effect may be achieved by performing the fusing operation in an aluminum or aluminum-lined vessel.

The catalysts employed in the present process may contain various concentrations of aluminum chloride, for example, from about 25% up to about 90%. The aluminum chloride, however, is always present in sufficient quantity to bind the catalyst promoter into a solid cake.

The aluminum chloride and promoter materials, preferably well mixed, are heated at a temperature of at least 190° C. (for instance, at about 200° C. to 300° C.) under a pressure of at least 40 pounds per square inch. Excellent catalysts may be prepared using pressure ranging

from about 100 to 800 pounds per square inch. The desired pressure may be imposed by air, N_2 , CO_2 , H_2 , HCl or the like. After heating the mixture for a few minutes or longer, the catalyst may be handled in either one of two ways. Catalysts of the maximum physical strength may be prepared by allowing the fused mass to cool and solidify, releasing the pressure and breaking the solid cake into fragments of the desired size. On the other hand, more porous catalysts exhibiting a maximum surface and light weight may be prepared by causing the fused catalyst mass to swell or froth by decreasing the pressure just prior to solidification. The porous cake is then crushed or ground in the usual manner, preferably in a dry atmosphere. Undersized fines produced in grading the catalyst in either case may be added to the next batch of catalyst. These catalysts are more fully described and claimed in our copending application, Serial No. 290,256, filed August 15, 1939, of which the present application is a continuation-in-part.

The isomerization, according to the present invention, may be executed in either the vapor phase, liquid phase or mixed phase. The lower boiling hydrocarbons, such as normal butane, are more preferably, but not necessarily, executed in the vapor phase. Higher boiling hydrocarbons, on the other hand, are usually more preferably isomerized in the liquid or mixed phase. In operation in the vapor phase the catalyst is preferably suspended as a fixed bed in a suitable reactor such as a tubular reactor or a catalytic case provided with means of establishing and maintaining the desired temperature, and the material to be isomerized is passed in the vapor phase at a suitable space velocity therethrough. In operation in the liquid phase the catalyst may be conveniently suspended as a fixed bed in an elongated tower through which the liquid hydrocarbon to be isomerized is percolated.

In order to realize the full activity of the catalyst it is most desirable to execute the isomerization in the presence of a hydrogen halide. The desired hydrogen halide may be added directly to the reaction zone of the feed or may be produced in the reaction zone by the addition of a small quantity of a substance which will react or decompose under the reaction conditions to liberate the desired hydrogen halide. Suitable materials of this latter category are, for example, water, alcohols, alkyl halides, etc. The amount of hydrogen halide preferably employed depends somewhat upon the particular circumstances. When executing the isomerization in the vapor phase a small amount of hydrogen halide, for example, 0.1% to 5%, may be added to the feed and removed from the product by a suitable washing treatment. It is preferable, however, when it is economically feasible, to recover the hydrogen halide from the product, for example, by fractional distillation, and to recycle the same through the reaction zone. In this way much higher concentrations of hydrogen halide, for example, 3% to 25%, may be economically employed. When operating in the liquid phase the hydrogen halide is preferably employed in such a concentration that its partial pressure over the reaction mixture is at least three atmospheres.

The isomerization process is usually executed at atmospheric pressure or somewhat elevated pressures, for example, 3 to 50 atmospheres. The prevailing pressure will depend somewhat upon the treating temperature but may also be

influenced by the deliberate addition of non-condensable gases such, in particular, as the hydrogen halide promoter, H_2 , etc. In general, the isomerization is effected at moderately elevated temperatures such, for example, as from about 50° C. to about 150° C. Lower or higher temperatures such, for example, as from room temperature up to about 300° C. may, however, be employed, if desired. Since, however, the object of the process is to isomerize saturated hydrocarbons or increase the ignition characteristics of saturated hydrocarbon fractions through isomerization, and since side reactions considerably decrease the efficiency and shorten the life of the catalyst, the temperatures or other conditions are not allowed to become so severe as to cause substantial degradation or other side reactions to take place.

The isomerization reaction is somewhat exothermic. When employing catalytic reactors of comparatively large cross section such as can be employed with the present catalysts, and particularly when the reaction temperature is adjusted not far below that at which appreciable side reactions begin, localized zones of higher temperature may be caused by the exothermic heat of reaction. This condition may be avoided by supplying the fresh feed at a plurality of points along the length of the catalyst bed.

Example I

Two parts by weight of powdered anhydrous aluminum chloride were mixed with one part of activated alumina previously crushed to 150 to 200 mesh and dried for two hours at 300° C. The mixture was placed in a pressure vessel equipped with heating means, the vessel closed, nitrogen introduced, and the whole heated to about 210° C. After heating for a time at a pressure of about 300 pounds per square inch, the mixture was gradually cooled and the pressure released prior to solidification, whereupon the mass swelled, or rose, and solidified into a hard porous cake. Upon crushing the cake and grading, an excellent catalyst of uniform composition and particle size, large surface area, high mechanical strength, low apparent density and low cost was obtained.

Normal butane vapor containing a small amount of HCl was passed at various rates at 11 atmospheres pressure through a reaction tube filled with the catalyst prepared as described and maintained at approximately 100° C. The following conversions to isobutane were obtained:

55	Space velocity (mols) (liter) (hr)	Conversion percent N-butane converted to isobutane
0.9		64
60	5.3	54

Example II

Normal butane vapor containing a small amount of HCl was passed at a space velocity of 5.4 mols per liter per hour and 150 pounds per square inch through a catalytic chamber filled with a catalyst prepared as described in Example I and maintained at 100° C. At the beginning, the conversion of normal butane to isobutane was about 46% to 48%. At the end of 318 hours of continuous operation, the conversion of normal butane to isobutane was still about 45%, and the catalyst showed no indication of exhaustion. Side reaction products were negligible.

As will be seen from these examples, the isomerization of normal butane (which is most difficult to isomerize) according to the present process takes place readily at comparatively low temperatures. Excellent conversions are obtained over protracted periods of time at high throughput rates.

The foregoing examples are submitted solely to illustrate the present process and the advantageous results obtainable thereby, and are not to be construed as limiting the invention.

We claim as our invention:

1. A process for the isomerization of saturated hydrocarbons comprising the step of contacting a saturated hydrocarbon fraction consisting essentially of saturated hydrocarbons containing from four to nine carbon atoms in the presence of a hydrogen halide at a temperature between 20° C. and 300° C. under isomerization conditions with a bed of a foraminous promoted aluminum chloride catalyst prepared by fusing together a finely divided mineral promoter selected from the group consisting of partially dehydrated siliceous and aluminous materials normally containing firmly bound water with sufficient anhydrous aluminum chloride to form a solid cake upon cooling, at a temperature of at least 190° C. under a pressure of at least 40 pounds per square inch, causing the fused mass to swell or foam by decreasing the pressure just prior to solidification, cooling the swollen mass to produce a foraminous cake, and breaking said foraminous cake into irregular fragments.

2. A process for the isomerization of butane comprising the step of contacting normal butane vapors in the presence of a hydrogen halide at a temperature between 50° C. and 300° C. under isomerization conditions with a bed of a foraminous promoted aluminum chloride catalyst prepared by fusing together a finely divided mineral promoter selected from the group consisting of partially dehydrated siliceous and aluminous materials normally containing firmly bound water with sufficient anhydrous aluminum chloride to form a solid cake upon cooling, at a temperature of at least 190° C. under a pressure of at least 40 pounds per square inch, causing the fused mass to swell or foam by decreasing the pressure just prior to solidification, cooling the swollen mass to produce a foraminous cake, and breaking said foraminous cake into irregular fragments.

3. A process for the isomerization of pentane comprising the step of contacting normal pentane in the vapor phase in the presence of a hydrogen halide under isomerization conditions with a bed of a foraminous promoted aluminum chloride catalyst prepared by fusing together finely divided mineral promoter selected from the group consisting of partially dehydrated siliceous and aluminous materials normally containing firmly bound water with sufficient anhydrous aluminum chloride to form a solid cake upon

cooling, at a temperature of at least 190° C. under a pressure of at least 40 pounds per square inch, causing the fused mass to swell or foam by decreasing the pressure just prior to solidification, cooling the swollen mass to produce a foraminous cake, and breaking said foraminous cake into irregular fragments.

4. A process for the isomerization of saturated hydrocarbons comprising the step of contacting a saturated hydrocarbon fraction consisting essentially of saturated hydrocarbons containing from four to nine carbon atoms in the presence of a hydrogen halide at a temperature between 20° C. and 300° C. under isomerization conditions with a bed of a foraminous promoted aluminum chloride catalyst prepared by fusing together a finely divided partially dehydrated alumina normally containing firmly bound water with sufficient anhydrous aluminum chloride to form a solid cake upon cooling, at a temperature of at least 190° C. under a pressure of at least 40 pounds per square inch, causing the fused mass to swell or foam by decreasing the pressure just prior to solidification, cooling the swollen mass to produce a foraminous cake, and breaking said foraminous cake into irregular fragments.

5. A process for the isomerization of butane comprising the step of contacting normal butane vapors in the presence of a hydrogen halide at a temperature between 50° C. and 300° C. under isomerization conditions with a bed of a foraminous promoted aluminum chloride catalyst prepared by fusing together a finely divided partially dehydrated alumina normally containing firmly bound water with sufficient anhydrous aluminum chloride to form a solid cake upon cooling, at a temperature of at least 190° C. under a pressure of at least 40 pounds per square inch, causing the fused mass to swell or foam by decreasing the pressure just prior to solidification, cooling the swollen mass to produce a foraminous cake, and breaking said foraminous cake into irregular fragments.

6. A process for the isomerization of pentane comprising the step of contacting normal pentane in the vapor phase in the presence of a hydrogen halide under isomerization conditions with a bed of a foraminous promoted aluminum chloride catalyst prepared by fusing together finely divided partially dehydrated alumina normally containing firmly bound water with sufficient anhydrous aluminum chloride to form a solid cake upon cooling, at a temperature of at least 190° C. under a pressure of at least 40 pounds per square inch, causing the fused mass to swell or foam by decreasing the pressure just prior to solidification, cooling the swollen mass to produce a foraminous cake into irregular fragments.
